(57) **CLAIM**

The ornamental design for a foldable camera bracket, as shown and described.

DESCRIPTION

FIG. 1 is a front, top, and side perspective view of a foldable camera bracket, in a folded configuration, showing the new design;

FIG. 2 is a left side view thereof;

FIG. 3 is a front, top, and side perspective view of the foldable camera bracket in an unfolded configuration;

FIG. 4 is a left side view thereof;

FIG. 5 is a front, top, and side perspective view of the foldable camera bracket, in a first angled configuration;

FIG. 6 is a left side view thereof;

FIG. 7 is a left side view thereof, showing a camera held on the foldable camera bracket in a horizontal position;

FIG. 8 is a left side view thereof, showing a camera held on the foldable camera bracket tilting at an angle;

FIG. 9 is a front, top, and right side perspective view of the foldable camera bracket, in a second angled configuration;

FIG. 10 is a right side view thereof;

FIG. 11 is a right side view thereof, showing a camera held on the foldable camera bracket in a horizontal position;

FIG. 12 is a right side view thereof, showing a camera held on the foldable camera bracket tilting at an angle;

FIG. 13 is a front, top, and left side perspective view of the foldable camera bracket, in a third angled configuration;

FIG. 14 is a left side view thereof;

FIG. 15 is a left side view thereof, showing a camera held on the foldable camera bracket in a horizontal position; and,

FIG. 16 is a side view thereof, showing a camera held on the foldable camera bracket tilting at an angle.

The recessed holes seen in FIGS. 3, 5, 9 and 13 penetrate through the foldable camera bracket.

The broken lines of even length illustrate environment and form no part of the claimed design.

The broken lines in FIGS. 7, 8, 11, 12, 15, and 16 depict environmental subject matter, specifically a camera, and form on part of the claimed design.

1 Claim, 8 Drawing Sheets
